Primary Examiner — Cathron Brooks*Assistant Examiner* — Karen E Kearney(74) *Attorney, Agent, or Firm* — Rader, Fishman & Grauer PLLC(57) **CLAIM**

The ornamental design for a storage medium, as shown and described.

DESCRIPTION

FIG. 1 is a front elevational view of a storage medium showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a front elevational view of another embodiment of a storage medium showing my new design;

FIG. 8 is a rear elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The broken lines shown are included for the purpose of illustrating unclaimed portions of the storage medium and form no part of the claimed design.
